UNITED STATES PATENT OFFICE.

WILLIS T. HURST, OF PITTSBURGH, PENNSYLVANIA, ASSIGNOR TO SLAG ROCK MACHINE COMPANY, A CORPORATION OF PENNSYLVANIA.

HOOK POSITIONER.

1,424,479.

Specification of Letters Patent. Patented Aug. 1, 1922.

Application filed March 31, 1920. Serial No. 370,207.

To all whom it may concern:

Be it known that I, WILLIS T. HURST, a resident of Pittsburgh, in the county of Allegheny and State of Pennsylvania, have 5 invented a new and useful Improvement in a Hook Positioner, of which the following is a specification.

In manufacturing plants where it is necessary to move articles by cranes, difficulty is experienced in bringing the crane hook into proper engagement with the article to be moved. This is particularly true in plants where large containers of highly heated molten material must be engaged by 10 a crane hook, as for example ladles used in the handling of hot metal or glass. Ladles containing such molten material are usually very hot and hence uncomfortable for a workman to approach. Also, there is a 15 certain amount of danger involved in standing close by such a ladle because of the possibility of an unforeseen disturbance of the molten material causing it to overflow or splash.

20 The object of this invention is to provide a crane hook positioner which will receive a crane hook, and which when such hook is in position for engaging the article to be moved, will move the hook into such 25 engagement.

The invention is illustrated in the accompanying drawings as adapted to attach a crane hook to a ladle adapted to contain molten metal, such as iron from a blast 30 furnace, although it will be understood that the invention is applicable to other specific uses. Fig. 1 is a combined elevation of the end of a ladle supported on a truck and vertical sectional view of the crank hook 35 positioner adjacent to the ladle, a crane hook also being illustrated in elevation just above the positioner; Fig. 2 a combined plan and sectional view taken on the line II-II, Fig. 1; Fig. 3 a left side view of the positioner as seen in Fig. 1, and Figs. 4 and 5 detail views of the positioner in which the parts are indicated in different relative positions which they assume when in operation.

The hook positioner comprises a movable 50 member adapted to receive a hook, and a latch or locking member adapted to hold the hook-receiving member in position for receiving the hook. The movable member is normally urged towards the article to

which it is desired to attach the crane hook, 55 and, when the hook has been received by the movable member, the latch is adapted to be released by the hook so that the movable member may move to cause the hook to engage the article desired to be moved by 60 the crane.

As previously stated the invention finds particular applicability to the attaching of a crane hook to a ladle. In the drawings there is illustrated a ladle 1 supported by 65 a truck 2 provided with end frames 4, upon each of which there is formed a pair of bearings 5 and 5^a which form trunnion supports for pins 3 and 3^a projecting laterally from the sides of the ladle. The general 70 construction of ladles of this sort, and the manner of supporting them on trucks are well known and do not require detailed explanation. At the bottom of the ladle there are attached U-shaped lugs 6 and 6^a, one 75 or the other of which may be engaged by a crane hook for the purpose of swinging the bottom of the ladle outwardly and upwardly on one of its pairs of trunnion supports 5 and 5^a. For example, if it is desired to swing the ladle on the axis of its pins 3, a crane hook 7 is attached to the lug 6, and as the hook is raised the bottom of the ladle swings outwardly, the end of the hook describing an arc the center of which 80 is the center of the pin 3. Operations of this sort take place, for example, when a ladle of molten iron is brought to a position in which the iron is poured into a runner leading to a pig-iron casting machine. 85

90 While the hook positioner may be constructed in other ways to operate in the manner explained above, the movable member preferably comprises a block 8 pivoted at one side, as at 9, to a suitable support 10, and provided on its other side with a hook-receiving guideway 11, which may be flared outwardly, or bell-shaped, at its top as seen particularly in Fig. 3. The weight of the block 8 and the position of its pivot point 100 9 with reference to the center of gravity of the block are such as to normally urge the block downwardly and outwardly towards the ladle. The means illustrated for holding the block upwardly in hook-receiving 105 position consists of a latch 12, pivoted at 13 to the support 10, and provided with a counter-weight 14 which tends to hold the

finger in upward position in engagement with a notch 19 formed on the lower edge of the block 8. The latch 12 is provided with a face 15 extending horizontally at the bottom 5 of the guideway 11 in a position to be struck by the lower end of the crane hook 7.

When it is desired to attach a crane hook to the lug 6, the hook is lowered by the crane operator into the guideway 11, the hook positioner parts being then in the relative positions illustrated in Fig. 1. The outward flaring of the upper end of the guideway gives sufficient leeway for the craneman to thus properly lower the hook. When the 15 crane hook reaches the bottom of the guideway 11, this position being indicated in full lines in Fig. 4, the lower end of the hook strikes the face 15 of latch 12, and the weight of the hook, acting through one side 20 of the pivot 13 of the latch causes the latch to swing upon its pivot so as to be released from its engagement of the detent or notch 19 of the block 8. The result is that the block swings upon its pivot 9 downwardly 25 and outwardly toward the ladle lug 6. The weight of the swinging block is sufficient to cause the crane hook to move towards the ladle, and to hold it in hooking position, the relative positions of the several parts in 30 this stage of the operation being indicated in dotted lines in Fig. 4. The hook is then raised by the craneman, and as it rises it engages the lug 6, as shown in full lines in Fig. 5, and swings the ladle 1 on its pivot 35 pin 3, the circular arc through which the hook passes being indicated by the line 16, Fig. 1. The outward and upward swinging of the ladle causes the rear side of the hook to bear against the block 8 and raise it to 40 a position in which the latch 12 may swing beneath the block into engagement with the notch 19 to lock the block in the position shown in Fig. 1.

After the metal has been poured from the 45 ladle, the ladle is returned to its normal position upon the truck 2, the crane hook 7 in no way interfering with the set position of the block 8 and latch 12. The hook is then lowered slightly so that it will swing 50 free of the lug 6, but will not strike the face 15 of the latch 12, and thereafter the hook may be readily moved upwardly through the guideway 11.

I claim:

- 55 1. The combination with a suspended vertically and laterally movable crane-hook, of means brought into action by descent of the crane hook to move the hook laterally into engagement with an object to be lifted.
- 60 2. A crane-hook positioner, comprising a movable hook-receiving and moving member, and means releasable by the movement of a crane-hook for normally holding said member in hook-receiving position.
- 65 3. A crane-hook positioner, comprising a

movable hook-receiving and moving member, and a latch for normally holding said member in hook-receiving position, said latch being releasable by a crane-hook as it moves downwardly, and said member being restored to hook-receiving position by said hook as it moves upwardly. 70

4. The combination with a crane hook, of a crane hook positioner comprising a movable hook-receiving and moving member 75 normally urged laterally and a latch for holding said member in hook-receiving position, said latch being releasable by travel of the crane-hook to permit said member to move said hook laterally. 80

5. The combination with a crane-hook, of a crane-hook positioner comprising a pivoted hook-receiving and moving block normally urged laterally by its weight, and a pivoted counterweighted latch for holding 85 said block in hook-receiving position, said latch being releasable by a crane hook as it moves downwardly, and said block being moved upwardly to latched position by the crane hook as the hook moves upwardly. 90

6. A crane-hook positioner, comprising a downwardly-urged pivotally mounted member provided with a guideway, a movable latch for holding said member in a substantially vertical position, said latch being releasable by a crane hook to permit said member to turn downwardly on its pivot point and thereby move said hook into engagement with an article to be moved. 95

7. A crane-hook positioner, comprising a 100 block pivotally mounted at one side and provided on its opposite side with a guideway, a pivotally mounted counterweighted latch adapted to engage the lower portion of said block and hold it in elevated position with its guideway lying in a substantially vertical position, said latch being provided with a horizontally extending face at the lower end of said guideway whereby the latch may be released by the weight of a 105 crane-hook to permit said block to turn downwardly on its pivot point and thereby move said hook into engagement with an article to be moved. 110

8. A crane-hook positioner, comprising a 115 hook-moving member movable to and from hook positioning position, and a latch normally holding said member from said position, said latch being releasable by the movement of a crane hook to permit said member to move the hook into engaging position with an object to be moved by the crane. 120

9. A crane-hook positioner, comprising a 125 hook-moving member movable to and from hook positioning position, and a latch normally holding said member from said position, said latch being releasable by the movement of a crane hook to permit said member to move the hook into engaging position with an object to be moved by the 130

crane, and said member being subsequently movable by the hook to a position to be again engaged by said latch.

10. A crane-hook positioner, comprising a hook-moving member movable to and from hook-positioning position, and a latch normally holding said member from said position, said latch being provided with a face lying in the path of movement of a descending crane-hook and adapted to be engaged by said hook to release the latch to permit said member to move the hook into engaging position with an object to be moved by the hook.
- 15 11. A crane-hook positioner, comprising a hook-moving member movable to and from hook-positioning position, and a latch nor-

mally holding said member from said position, said latch being provided with a face lying in the path of movement of a descending crane-hook and adapted to be engaged by said hook to release the latch to permit said member to move the hook into engaging position with an object to be moved by the hook, and said hook-moving member being provided with a face against which the hook bears on its upward movement and in consequence thereof moves said member to a position to be again engaged by said latch.

In testimony whereof, I have hereunto set my hand.

WILLIS T. HURST.
